UNITED STATES PATENT OFFICE.

HENRY ADAMS, OF NEW LONDON, CONNECTICUT, ASSIGNOR TO THE ADAMS MINING MACHINERY CORPORATION, OF NEW LONDON, CONNECTICUT, A CORPORATION OF NEW YORK.

NON-ATTRITION PROCESS OF AND APPARATUS FOR WASHING AND SORTING COAL.

1,224,350.

Specification of Letters Patent.

Patented May 1, 1917.

Application filed May 11, 1916. Serial No. 96,774.

To all whom it may concern:

Be it known that I, HENRY ADAMS, a citizen of the United States, residing in New London, in the county of New London 5 and State of Connecticut, have invented certain new and useful Improvements in Non-Attrition Processes of and Apparatus for Washing and Sorting Coal, of which the following is a specification.

This invention relates to a process for lowering, washing, sizing and separating minerals and ores of different specific gravities, and especially anthracite coal, and the apparatus for carrying out such process.

One of the main objects of the present invention is to provide a process whereby the finer elements of a quantity of mineral, ore or coal that is being sorted will be carried with jets of water or the like into troughs 15 separated from one another, each provided for one of the series of jets of water, and the heavier elements will be dropped into lower compartments, the heavier of such 20 heavier elements dropping into the compartments nearest to the inlets of such jets while the lighter of such elements drop into the compartments farther away from such 25 jets.

For carrying out the process, an apparatus is disclosed particularly adapted for 30 grading coal. By means of this apparatus, it will be seen that the heavier particles may be removed without first draining the water by which they have been washed, and 35 only the receptacles or troughs for the lighter elements require drainage of water before removal.

These and other features, capabilities and 40 advantages of the invention will appear from the subjoined detail description of one specific embodiment thereof illustrated in the accompanying drawings in which—

Figure 1 is a fragmental front elevation of the apparatus, partially broken away.

Fig. 2 is a sectional view of the portion 45 of the apparatus used for separating the slate and unrelated elements and the coal from one another.

Fig. 3 is a sectional view of the portion 50 of the apparatus shown in Fig. 1 as used for separating the several grades of coal from one another.

In the portion of the embodiment shown in Figs. 1 and 2, a main housing A is pro-

vided preferably of long narrow construction having a rear wall 11 and provided with three elongated inlet slots 12, 13 and 14 and front wall 15, having three elongated outlet slots 16, 17 and 18 of greater widths than the slots 12, 13 and 14; a roof member 19 having an elongated opening 20 therein adjacent to the rear wall 11; and a floor member 21 provided with partitions 22 extending upward therefrom to form the troughs 23.

Extending down from the elongated opening 20 in the roof member 19 there are flange portions 24 converging downwardly to form a suitable mouth for receiving the coal to be graded preparatory to feeding 70 the same into the housing A. Extending along the slots 12, 13 and 14 are the tubes 25, 26 and 27 respectively each connected to the stand pipe 28 by suitable connections 29, 75 30 and 31 respectively. The connections 29, 30 and 31 are each provided with a control valve 32. The stand pipe 28 is suitably connected to a reservoir 33 to which reservoir 33 the water or a suitable liquid 80 is pumped by the pump 34. The reservoir is also provided with a suitable control valve 35.

The outside of the front wall member 15 is suitably equipped with troughs 35, 36 and 37 each secured adjacent to the lower 85 edges of the openings 16, 17 and 18 respectively. The troughs 35, 36 and 37 have their outer wall members extending upward beyond the upper edges of the openings 16, 17 and 18 and their lower portions extending 90 at an inclination to the horizontal to facilitate the water or liquid that may collect therein.

For conveying the coal to be treated in the housing A to the opening 20, suitable 95 elevator L is provided suitably guided by the sprockets 38 and provided with buckets 39 or the like.

In the troughs 23, suitable receptacles 40 which may be movable conveyers are provided.

The tubes 25, 26 and 27, are provided with suitable openings such as perforations, whereby water that is conveyed to such tubes may be discharged therefrom through 105 the openings 12, 13 and 14 across the interior of the housing A to the openings 16, 17 and 18 to be discharged therefrom.

The portion of the embodiment illustrated in Fig. 3 consists essentially of a housing A' similar to the housing A, having a rear wall 11' provided with openings 12', 13' and 14'; a front wall 15' provided with openings 16', 17' and 18'; a roof member 19' provided with the openings 20' and a partition member 22' extending parallel to the wall members 11' and 15' and dividing the bottom of the housing A' into two trough members 23'.

On the outside of the rear wall member 11' tubes 25', 26' and 27' are provided which similar to the tubes 25, 26 and 27 are also connected to a reservoir and pump by means 15 of which water may be fed to such tubes 25', 26' and 27'.

As illustrated in Fig. 2 the openings 16, 17 and 18 are disposed at a lower level than the openings 12, 13 and 14, for this purpose, 20 the discharge perforations of the tubes 25, 26 and 27 will be set accordingly. It will also be seen that the openings 16 and 18 are disposed at lower levels than their co-operating openings 12 and 14 relative to the 25 lower level of the opening 17 to its co-operating opening 13. This is provided to exercise various degrees of impetus by the water jets on the coal being treated.

Disposed above the opening 20 there is 30 provided a suitable hopper 41 to receive the coal from the buckets 39 of the elevator L preparatory to discharging the same into the mouth of the housing A.

On the outside of the front wall 15', inclined troughs 35', 36' and 37' are secured adjacent to the openings 16', 17' and 18' respectively. The levels of the openings 16', 17' and 18' relative to the openings 12', 13' and 14' are similar to the difference in levels of the openings 16, 17 and 18 relative to the openings 12, 13 and 14 of the housing A.

Secured to the inner side of the roof member 19' the inwardly extending flange portions 24' are secured converging toward one 45 another to provide a mouth to the housing A' similar to the mouth of the housing A.

Disposed above the opening 20' is provided a suitable hopper 41' to receive the coal proprietary to discharging the same into 50 the mouth of the housing A', such hopper 41' receiving the coal from the buckets of an elevator passing across the same similar to the buckets 39 of the elevator L of the housing A.

55 The steps of the process consist substantially of the following: The coal after having been broken to suitable sizes and before the slate and other foreign material have been removed therefrom is discharged into 60 the mouth of the housing A'. The slate having a greater specific gravity than coal when coming into contact with jets of water or the like discharged by the tubes 25', 26' and 27' will not be deflected thereby and 65 is permitted to drop into the trough 23' ad-

jacent to the rear wall member 11'. The coal therefore will be deflected by such jets of water to drop into the trough 23' adjacent to the front wall member 15', and the lighter elements contained in the mixture such as coal dust, and very fine grades of coal will be carried with the jets of water into the troughs 35', 36' and 37', the heavier of such elements naturally being conveyed to the lower trough 37'. In this way, the slate will be separated from the coal, and some of the finer grades of coal separated from the heavier grades, such finer grades settling in the troughs 35', 36' and 37' ready for removal after the water has been drained 80 from such troughs.

Thereupon the coal contained in the trough adjacent to the front wall member 15 is conveyed to the buckets 39 of the elevator L to be discharged into the housing A for further sorting. As the coal drops from the mouth of the housing A the force of the jets of water and the distance the jets are spaced from one another will be so regulated and other elements will be so regulated that the 90 heavier grades of coal will not be materially deflected when coming into contact with the jets of water and will be permitted to drop into the receptacle 40 adjacent to the rear wall 11.

95 For the purpose of explanation let us suppose that the grade collected in the receptacle adjacent to the rear wall 11 will be the grade generally designated as "stove." The next lighter grade of coal, for instance the "chestnut" grade, will be sufficiently deflected by the jets of water to drop into the intermediate receptacle 40 and the grade lighter than the chestnut as for instance "pea" grade will drop into the receptacle 40 adjacent to the front wall member 15. The still lighter grades including coal dust and like that may still be contained in the mixture conveyed to the housing A will be carried with the jets of water according to 100 their specific gravities and deposited in the troughs 35, 36 and 37 from which they may be removed after the drainage of the water from such troughs.

105 It is obvious that various changes and modifications may be made to the steps of the process of the apparatus for carrying out such process without departing from the general spirit of the invention.

I claim:

1. A process of treating minerals, ores, coal and the like consisting in conveying the same to an apparatus, permitting such elements to be freely gravitationally dropped down through the apparatus, discharging free, individual jets of water under pressure against the falling material during its gravitational passage through the apparatus, so that the elements will be deflected and dropped into different troughs 120

at the bottom of such apparatus according to their weight, permitting the discharge of such jets out of the apparatus at different levels into other troughs spaced from one another, so that the dust and finer elements of the mixture that may be carried with such jets will be deposited in said other troughs according to their weights.

2. An apparatus for treating coal and the like having a frame, there being a plurality of elongated inlet openings spaced from one another at different levels, a plurality of elongated outlet openings also spaced from one another at different levels one for each of said inlet openings, means for discharging jets of water from said inlet openings across the apparatus to said outlet openings and out through the same, a plurality of troughs in the bottom of said apparatus spaced from the inlet openings in a graduated manner, there being a mouth at the top of said apparatus, and means for conveying coal to such mouth to permit the same to drop therefrom, to be actuated upon by the several jets of water so that the elements according to their weight may be permitted to drop in different troughs at the bottom of said apparatus and the lighter elements be carried with the jets of water and out through several outlet openings according to their weight.

3. An apparatus for treating coal and the like having a frame, there being a plurality of elongated inlet openings spaced from one another at different levels, a plurality of elongated outlet openings also spaced from one another at different levels one for each of said inlet openings, means for discharging jets of water from said inlet openings across the apparatus to said outlet openings and out through the same, a plurality of troughs in the bottom of said apparatus spaced from the inlet openings in a graduated manner, there being a mouth at the top of said apparatus, means for conveying coal to such mouth to permit the same to drop therefrom, to be actuated upon by the several jets of water so that the elements according to their weight may be permitted to drop in different troughs at the bottom of said apparatus and the lighter elements be carried with the jets of water and out through several outlet openings according to their weight, and other troughs being secured to said apparatus adjacent to the outlet openings to receive the water discharged therethrough and the finer elements of coal carried therethrough.

4. An apparatus for treating coal and the like having a frame, there being a plurality of elongated inlet openings spaced from one another at different levels, a plurality of elongated outlet openings also spaced from one another at different levels one for each of said inlet openings, means

for discharging jets of water from said inlet openings across the apparatus to said outlet openings and out through the same, a plurality of troughs in the bottom of said apparatus spaced from the inlet openings in a graduated manner, there being a mouth at the top of said apparatus, means for conveying coal to such mouth to permit the same to drop therefrom, to be actuated upon by the several jets of water so that the elements according to their weight may be permitted to drop in different troughs at the bottom of said apparatus and the lighter elements to be carried with the jets of water and out through several outlet openings according to their weight, and other troughs being secured to said apparatus adjacent to the outlet openings to receive the water discharged therethrough and the finer elements of coal carried therethrough, the troughs being inclined to the horizontal to permit the drainage of the water while the finer elements will settle in said troughs.

5. A process of treating minerals, ores, coal and the like consisting in conveying the same to a washing and grading apparatus; permitting such elements to be dropped down into the apparatus; discharging a plurality of superposed jets of water against the stream of such elements during their passage through the apparatus at such pressure that the more valuable commercial elements will be deflected and deposited into different grades at the bottom of such apparatus according to their respective weights and fineness; the discharge of such jets through the apparatus being at different levels spaced from one another, at an angle to the line of passage of the material or elements being washed and graded, so as to deposit the finer less valuable elements into different grades; so that the dust and finer elements of the mixture that may be carried with such jets will be deposited according to their respective weights and fineness.

6. A process of treating minerals, ores, coal and the like consisting in conveying the same to a washing and grading apparatus; permitting such elements to be freely gravitationally dropped down into and through the apparatus; discharging a plurality of superposed jets of water against the stream of such elements at an angle thereto, during their passage through the apparatus, at such pressure that the more valuable commercial elements will be deflected and deposited into different grades at the bottom of such apparatus according to their respective weights and fineness; and causing the discharge of such jets through the apparatus at different levels spaced from one another and at such pressures as to deposit the finer materials into different additional grades, so that the dust

and finer elements of the mixture that may be carried with such jets will be deposited according to their respective weights and sizes, the angle of impingement of each of the jets upon and through the stream of material being different and increasing in horizontality from top to bottom.

7. A process of treating minerals, ores, coal and the like consisting in conveying the same to a washing and grading apparatus; permitting such elements to be freely gravitationally dropped down into and through the apparatus; discharging a plurality of superposed jets of water against the stream of such elements at an angle thereto, during their passage through the apparatus, at such pressure that the more valuable commercial elements will be deflected and deposited into different grades at the bottom of such apparatus according to their respective weights and fineness; and causing the discharge of such jets through the apparatus at different levels spaced from one another and at such pressures as to deposit the finer materials into different additional grades, so that the dust and finer elements of the mixture that may be carried with such jets will be deposited according to their respective weights and sizes, the angle of impingement of each of the jets upon and through the stream of material being different.

8. A process of treating minerals, ores, coal and the like consisting in conveying the same to a washing and grading apparatus; permitting such elements to be freely gravitationally dropped down into and through the apparatus; discharging a plurality of superposed jets of water against the stream of such elements at an angle thereto during their passage through the apparatus at such pressure that the more valuable commercial elements will be deflected and deposited into different grades at the bottom of such apparatus according to their respective weights and fineness; the discharge of such jets through the apparatus being at different levels spaced from one another so as to deposit the finer less valuable elements into different grades; so that the dust and finer elements of the mixture that may be carried with such jets, will be deposited according to their respective weights and fineness; the deflecting substantially horizontal grading and deflecting water-jets impinging against and passing through the mass or stream of falling material to be graded in the form of thin sheets.
